UNITED STATES PATENT OFFICE.

ANNIE L. WESTBROOK, OF LORENA, TEXAS.

DESIGN FOR A MEDICINE-SPOON.

52,688.

Specification for Design.

Patented Nov. 12, 1918.

Application filed July 24, 1918. Serial No. 246,605. Term of patent 14 years.

To all whom it may concern:

Be it known that I, ANNIE L. WESTBROOK, a citizen of the United States, residing at Lorena, in the county of McLennan and State of Texas, have invented a new, original, and ornamental Design for Medicine-Spoons, of which the following is a specification, reference being had to the accompanying drawing, forming part thereof.

The figure is a perspective view of a medicine spoon, showing the new design.

I claim,

The ornamental design for a medicine spoon, as shown.

In testimony whereof I affix my signature.

ANNIE L. WESTBROOK.
